DESIGN FOR A GEM SETTING

Theodore E. Syman, Denver, Colo.

Application April 22, 1941, Serial No. 100,562

Term of patent 14 years

To all whom it may concern:

Be it known that I, Theodore E. Syman, a citizen of the United States, residing at Denver, in the county of Denver and State of Colorado, have invented a new, original, and ornamental Design for a Gem Setting, of which the following is a specification, reference being had to the accompanying drawing, forming part thereof.

Figure 1 is a top plan view, Figure 2 an end elevation, Figure 3 a bottom plan view, and Figure 4 a side elevation of a gem setting showing my new design.

I claim:

The ornamental design for a gem setting, as shown.

THEODORE E. SYMAN.
